(57) **CLAIM**

The ornamental design for an all in one keyboard, as shown and described.

DESCRIPTION

FIG. 1 is a front perspective view of the all in one keyboard; FIGS. 2 and 3 are respectively top and bottom views of the all in one keyboard;

FIGS. 4 and 5 show alternate side views of the all in one keyboard; and,

FIGS. 6 and 7 show respectively front and rear views respectively of the all in one keyboard.

The broken lines in the drawings are for the purpose of illustration and forms no part of the claimed design.
